UNITED STATES PATENT OFFICE.

ARTHUR TREVOR DAWSON AND GEORGE THOMAS BUCKHAM, OF WESTMINSTER,
LONDON, ENGLAND, ASSIGNEES TO VICKERS LIMITED, OF WESTMINSTER,
LONDON, ENGLAND.

GUN-MOUNTING.

1,302,522.

Specification of Letters Patent.

Patented May 6, 1919.

Application filed April 15, 1915. Serial No. 21,622.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to Gun-Mountings, of which the following is a specification.

This invention relates to gun-mountings and has particular reference to naval mountings of the kind proposed by us in which the side cheeks of the carriage, instead of being provided with the usual center pivot, are extended downward and made integral with or suitably connected to a rotary chamber for the accommodation of the gun layers.

According to this invention the elevating mechanism in addition to being actuated by the elevating number through the usual hand wheel or crank is also capable of being actuated by the same elevating number through pedals suitably connected to the elevating mechanism. In this manner we avoid the necessity for employing an auxiliary elevating number for effecting the movement of the gun and sight through the large angles necessary to counteract the effect of the ship's movements on the laying of the gun, the single elevating number performing this movement by means of the aforesaid pedals. Similarly the training mechanism may be under the control of a hand wheel or crank and pedals, both of which are operated by a single training number, the pedals being employed for moving the mounting when large variations in training are to be effected. By avoiding the necessity for employing an auxiliary elevating or training number, additional sighting gear with a consequent larger sight opening in the shield (when the latter is fitted) is dispensed with.

In order that the said invention may be clearly understood and readily carried into effect we will describe the same more fully with reference to the accompanying drawings, in which:

Figures 1 and 2 are respectively a sectional side elevation and a sectional plan showing, in a more or less diagrammatic manner, a gun mounting provided with ele-

vating and training mechanism constructed in accordance with our invention.

Fig. 3 is a side elevation on a larger scale showing a constructional form of the improved elevating or training mechanism, and

Fig. 4 is a section taken approximately on the line 1—1 of Fig. 3.

The gun mounting shown by Figs. 1 and 2 is similar to that already proposed by us, comprising a chamber A which is rotatably mounted in the deck in the case of a naval mounting, and is integral with or connected to the side cheeks A', A' between which the elevating and training numbers are disposed. The chamber A carries two seats a, a one for the elevating and the other for the training number. Arranged in a convenient position relatively to the seats a, a are the elevating handwheels or cranks B, B and the corresponding pedals B', B'. The handwheels or cranks and the pedals are carried by brackets attached either to the side cheeks A', A' or to the chamber A.

Referring more particularly to Figs. 3 and 4, which are assumed to show the elevating mechanism, the elevating hand wheel or crank B is connected by bevel gearing for example, to a shaft b which is hereinafter referred to as the main elevating shaft, and the pedals B' are connected also through bevel gearing with a shaft b' which is hereinafter termed the auxiliary elevating shaft. The main elevating shaft b carries a worm b² gearing with a worm wheel B² loosely mounted on a shaft C carrying the elevating pinion C'. The auxiliary elevating shaft b' also carries a worm b³ gearing with a worm wheel B³ also loosely mounted on the shaft C. These worm wheels have rigidly connected to them bevel wheels B^{2x}, B^{3x} which gear with bevel pinions b^{2x}, b^{3x} rotatably mounted on pins carried by a sleeve B⁴ which is rigidly connected to the shaft C. This gearing constitutes a differential gear between the hand wheel or crank B, the pedals B' and the elevating pinion C'. By these means the handwheel or crank and the pedals can be operated independently or simultaneously to move the gun; by operating them simultaneously the elevating number can exert an increased amount of power upon the elevating mechanism so that large movements of the gun can be effected with

the minimum inconvenience to the elevating number; the final gradual movement of the gun to bring the sight upon the target can then be made by means of the handwheel or 5 crank with the elevating number in a more composed condition than would have been the case if he had been compelled to move the gun through large angles by the hand wheel or crank alone.

10. It will be understood that similar mechanism may be employed for the training handwheel or crank and the training pedals, and also that any other form of mechanism can be used for the purpose of enabling the 15 elevating or training handwheel or crank and the pedals to be operated independently to move the gun.

What we claim and desire to secure by Letter's Patent of the United States is:—

20. 1. In a gun mounting, the combination with the elevating gear, of a hand operated device for actuating said gear and a foot operated device for actuating said gear, said devices being operable by the same gunner 25 and the foot operated device being auxiliary to the hand operated device.

2. In a gun mounting, the combination with the training gear, of a hand operated device for actuating said gear and a foot 30 operated device for actuating said gear, said devices being operable by the same gunner and the foot operated device being auxiliary to the hand operated device.

3. In a gun mounting, the combination 35 with the elevating gear, of a hand operated device for actuating said gear, pedals also serving to actuate said gear, said device and pedals being operated by the same gunner, and means for enabling said device and the 40 pedals to be operated either simultaneously or independently, said pedals being auxiliary to the hand operated device.

4. In a gun mounting, the combination with the training gear, of a hand operated 45 device for actuating said gear, pedals also serving to actuate said gear, said device and pedals being operated by the same gunner, and means for enabling said device and the

pedals to be operated either simultaneously or independently, said pedals being auxiliary to the hand operated device. 50

5. In a gun mounting, the combination with the elevating gear, of a hand operated device for actuating said gear, pedals also serving to actuate said gear, said device and 55 pedals being operated by the same gunner, and differential gear interposed between said elevating gear and the said device and pedals, said pedals being auxiliary to the hand operated device.

6. In a gun mounting, the combination with the training gear, of a hand operated device for actuating said gear, pedals also serving to actuate said gear, said device and 65 pedals being operated by the same gunner, and differential gear interposed between said training gear and the said device and pedals, said pedals being auxiliary to the hand operated device.

7. In a gun mounting, the combination 70 with the elevating gear, of a hand operated device for actuating said gear, a foot operated device for actuating said gear, said devices being operated by the same gunner and the foot operated device being auxiliary 75 to the hand operated device, and a chamber moving with the gun in training for accommodating said foot operated device and the gunner's legs.

8. In a gun mounting, the combination 80 with the training gear, of a hand operated device for actuating said gear, a foot operated device for actuating said gear, said devices being operated by the same gunner and the foot operated device being auxiliary 85 to the hand operated device, and a chamber moving with the gun in training for accommodating said foot operated device, and the gunner's legs.

In testimony whereof we affix our signatures in the presence of two witnesses.

ARTHUR TREVOR DAWSON.
GEORGE THOMAS BUCKHAM.
